ELECTRODE CONSTRUCTION FOR ELECTROLUMINESCENT TUBES

Roy R. Wiley and Alfred L. Brandt, Buffalo,
N. Y., assignors to Flexlume Corporation, Tonawanda, N. Y., a corporation of New York

Application November 17, 1928, Serial No. 320,150

1 Claim. (Cl. 176—126)

This invention relates in a general way to electroluminescent tubes which employ an inert gas such as neon as the luminescent medium and more particularly to the electrode construction of the tubes.

The principal object of the invention is a construction in which provision is made for protecting those portions of the lead-in wires in the vicinity of the electrodes against the disintegrating action of the electric current which is utilized to energize the tubes.

Embodiments of the invention are illustrated in the accompanying drawing, wherein:

Figure 1 is a longitudinal sectional view of the electrode construction in relation to the terminal portion of a tube.

Figure 2 is a section along line 2—2 of Figure 1.

Figure 3 is a longitudinal sectional view similar to Figure 1 showing a modified form of construction.

Figure 4 is a section along line 4—4 of Figure 3.

The tube 1 is sufficiently indicated by showing the terminal portion thereof in which the reentrant flare is provided with a glass seal 2 through which the lead-in wire 3 passes. The electrode 4 to which the lead-in wire is connected may be composed of any suitable material and fashioned in any suitable form. Preferably it is composed of copper of foraminous structure and arranged in the form of a cylinder.

The electrode 4 is arranged within a chamber provided by a hollow member 5 of glass or other suitable insulating material which may be of any suitable form and supported in any suitable manner. As shown and preferred, the hollow member is made of cylindrical shape having the end through which the lead-in wire passes, closed as at 6. The electrode is preferably although not necessarily anchored in the hollow member. This may be accomplished by heating the hollow member so as to cause it to flow into and fill the foramina in the electrode, leaving a suitable area of the latter exposed as an active area. While the anchorage of the electrode in this manner considerably decreases the electrode surface otherwise available as an active area, this reduction of active surface in no way impairs the operation of the tube.

The hollow member is axially located within the tube, preferably by an axially disposed glass cylinder 7, the opposite ends of which are provided with annular supporting flanges 8 of a diameter substantially equal to the inside diameter of the tube, the hollow member being thereby substantially spaced concentrically from the wall

of the tube with resultant thermal and electrical insulation from said wall. The supporting flanges 8 also function to reduce the area of the gas-path extending along the outer face of the cylinder 7 and thereby increase the electrical resistance of such path to an extent such as to prevent any electrical discharge action from taking place around the axially located uninsulated portion 3a of the lead-in wire 3 between the glass seal 2 and the hollow member 5. In this connection, it should be noted that when any uninsulated portion of the lead-in wire 3 is permitted to extend along the axial center of a tube with a comparatively low resistance gas-path connecting it to the tube proper, such portion will be subject to a discharging action. This result is greatly to be avoided inasmuch as it is very apt to destroy the lead-in wire, rendering the tube inoperative. While it can be avoided by increasing the electrical resistance of the connecting path as indicated above and also by insulating the lead-in wire from the connecting path, we have observed that it is effectively prevented by the simple expedient of substantially offsetting the lead-in wire from the axial center of the tube. This last mentioned method is utilized to protect that portion of the lead-in wire extending within the electrode chamber, such portion being substantially offset.

From the construction thus far described, it is evident that the active area of the electrode—i. e. the area in which the current can actually enter or leave the electrode—is entirely contained within the electrode chamber. Consequently all of the current flowing through the tube is compelled to flow into and/or out of the electrode chamber. With this in mind it may be pointed out that the present invention is concerned mainly with the communication between the electrode chamber and the tube proper.

Generally stated, the invention consists in restricting or obstructing the communication between the electrode chamber and the tube proper. The nature of the action which takes place as a result of this type of construction is not, at this time, fully understood but its beneficial effects are apparent. One surprising feature resulting from this construction, is the very great decrease in the effective rate at which the volatilized metal is deposited. Whether or not this result is due to a decrease in the rate of volatilization or to the revolatilization of the deposited metal, has not yet been determined. Whatever the cause, it may be said that the rate at which the deposit accumulates, decreases as the communication is relatively more restricted or ob-

structed while the amount of such deposit is comparatively small under all conditions of operation.

A further effect resulting from this construction is the decrease in the tendency of the deposit to "creep" along the wall of the hollow member. So far as we have been able to determine, any restriction, however slight, will, to some extent at least, effect a decrease in the tendency of the deposit to "creep" but will not, necessarily, overcome such tendency. There seems to be a critical value of restriction below which the deposit will "creep" more or less, and above which it is entirely confined within the hollow member even though the current values be increased several times in excess of their normal operating rating. In other words, the greater the restriction within the limit of practicability the better the result. It is apparent that such metal as is detached from the body of the electrode and confined within the hollow member, will be maintained at a relatively high temperature so that the rate at which the inert gas is occluded is very materially reduced. Furthermore, it is evident that the confinement of the deposit to the electrode chamber favors the re-uniting of the deposit with the electrode whereby the life of the latter is indefinitely prolonged.

As a result of the features noted, we have found that the electrode can be made extremely small and operated at a relatively high temperature without any danger of the electrode disintegrating or being consumed and with a rate of gas-occlusion which is so small as to be negligible, the result being that a tube in which the present invention is utilized will have an effective life several times greater than that of tubes heretofore used.

The communication between the electrode chamber and the tube proper may be restricted or obstructed in any suitable manner. In the preferred embodiment, the obstruction is effected by the simple expedient of reducing the diameter of the hollow member 5 at its open end to form a relatively contracted connecting passage 9. In this construction it is obvious that the value of the obstruction afforded by the passage 9 can be increased by further reducing its diameter and/or increasing its length. It is equally obvious that a decrease in the diameter of the passage or an increase in its length will effect an increase in its electrical resistance. Hence while the beneficial effects noted continually improve as the communication is more and more obstructed, the extent to which the obstruction can be carried out is limited by the increase in the electrical resistance of the communication. In other words, the beneficial effects improve as the communication resistance is increased; hence the latter factor places a practical limit upon the extent to which the obstruction can be carried out.

The opening or passage 9 should in any case be less in diameter than the minimum diameter of the electrode 4, whereby the electrode is removed from the direct effect of the intensely active axially located column of gas within and adjacent the ends of the passage 9. Very good

results, superior in degree to constructions heretofore used, have been obtained, for example, with a tube of 19 millimeters diameter having a neon pressure of 8 to 10 millimeters of mercury, a hollow member of the form shown in Figure 1 having a maximum inside diameter of 5 millimeters with a restricted passage 9 of 3 millimeters diameter and about 3 millimeters length and an electrode 4 enclosed within the hollow member and having a length of 10 millimeters and a minimum diameter of 4 to 4½ millimeters, the operating current having a value of approximately 25 milliamperes. Of course, the proportions of the parts may be varied indefinitely while utilizing the principles and obtaining the benefits of the invention as herein pointed out. It will, of course, be understood that the tube is initially prepared in the usual manner and it is noted that the electrode despite its small size, very effectively carries and withstands the heavy preliminary bombardment currents.

The means by which the communication between the electrode chamber and the interior of the tube proper is restricted or obstructed may take various forms. In Figures 3 and 4, we have shown a different construction for accomplishing the same result. In this construction, the hollow member 5 is in the form of a cylinder of uniform bore from its closed end to its open end. The open end is, however, covered by a cap 10 which is secured to the hollow member. The cap is of such form as to define an annular passage 9a extending from the open end of the hollow member around its adjacent edge and rearwardly along its outer surface to a series of apertures 11 formed in the cap and through which communication with the tube proper is established. The lead-in wire 3 in this construction, is protected and the hollow member 5 supported by a glass sleeve 12 which extends inwardly of the tube from the glass seal 2. Strictly speaking, if the term "restricted" be regarded as contemplating an aspect of relative size, the communication illustrated in Figures 3 and 4 is obstructed rather than restricted but the results seem to be the same. Since the restriction of a communication has an aspect of obstruction, it may be noted that both forms may be generically regarded as obstructed communications between the electrode chamber and the tube wherein the electrode is removed or remote from the direct effects of the column of gas within and adjacent the ends of the obstructed passage.

Having fully described our invention, we claim:

An electrode construction for electroluminescent tubes comprising in combination with such a tube, a body arranged within said tube and formed with an electrode chamber, an electrode arranged along the wall of said chamber and a lead-in wire extending through a wall of said chamber into the same, said lead-in wire being connected to the electrode and having that portion extending into the electrode chamber substantially offset from the axial center of the tube, thereby being protected from direct exposure to the axial center of discharge.
